UNITED STATES PATENT OFFICE.

LANGDON WASHINGTON MOORE, OF BOSTON, MASSACHUSETTS, ASSIGNOR
TO FRANK THOMPSON, OF WEST SWANZEY, NEW HAMPSHIRE.

DESIGN FOR A HAMMOCK-SLING.

SPECIFICATION forming part of Design No. 34,307, dated April 2, 1901.

Application filed March 5, 1901. Serial No. 49,975. Term of patent 14 years.

To all whom it may concern:

Be it known that I, LANGDON WASHINGTON MOORE, a citizen of the United States, residing at Boston, in the county of Suffolk and State of Massachusetts, have invented and produced a new and original Design for a Hammock-Sling, of which the following is a specification, reference being had to the accompanying drawings, forming part thereof.

Figure 1 is a front elevation of a hammock-sling, showing my new design. Fig. 2 is a side elevation of a hammock-sling, showing my new design.

As shown in the drawings, the leading or material features of my new design consist in its upper portion of the overhanging curved portions *a a*, that spring from the common part *b*, from which incline downwardly and outwardly the ribs *c*. From near the middle point of each of the ribs *c* incline downwardly and inwardly the ribs *d*, thus inclosing with the ribs *c* a diamond-shaped opening *e*. The lower ends of the ribs *c* are formed into the outer eyes *f*, and the lower ends of the ribs *d* meet to form the middle eye *g*. The lower portion of my new design is formed of a cen-

tral curved part *h*, which incloses a pear-shaped opening *i*. The upper end of the central part *h* is formed into a middle eye *j*, and from the middle portion of the base of the central part *h* projects outwardly and upwardly a hook-shaped part *k*. From near the middle point of each of the sides of the central part *h* incline upwardly and outwardly the ribs *l*, the upper ends of which are formed into the outer eyes *m m*. The outer eyes *m* and the outer eyes *f* are joined by spirals *n n*, and the middle eye *g* and the middle eye *j* are joined by a like spiral *o*.

Having described my invention, what I claim as new, and desire to secure by Letters Patent, is—

The design for a hammock-sling, as herein shown and described.

In testimony whereof I have signed my name to this specification in the presence of two subscribing witnesses.

LANGDON WASHINGTON MOORE.

Witnesses:

FRANK THOMPSON,
JAMES HAMILTON.
